INVENTOR

Victor J. Evans

ATTORNEY

[Signature]
WITNESS:

UNITED STATES PATENT OFFICE.

PAUL JOHN TUMULLA, OF CHICAGO, ILLINOIS.

WRENCH.

1,371,952.

Specification of Letters Patent. Patented Mar. 15, 1921.

Application filed March 22, 1920, Serial No. 367,784. Renewed February 8, 1921. Serial No. 443,493.

To all whom it may concern:

Be it known that I, PAUL J. TUMULLA, a citizen of the United States, residing at Chicago, in the county of Cook and State of Illinois, have invented new and useful Improvements in Wrenches, of which the following is a specification.

This invention relates to a wrench and has for its primary object the construction 10 of a wrench in which the various parts are so constructed and associated that an adjustment may be more quickly accomplished and besides the object more effectively gripped.

15 An object of the invention is the novel manner of connecting the handle member so that the teeth thereof may be accurately associated with the teeth of the shank.

20 A feature of my invention is the use of a movable gripping member so that the object may be more effectively gripped.

With these and other objects in view the invention will be better understood from the 25 following detailed description taken in connection with the accompanying drawing wherein:

Figure 1 is a side elevation of a wrench constructed in accordance with my invention.

30 Fig. 2 is a similar view with the plate removed.

Fig. 3 is a detailed sectional view through the gripping member.

Again referring to the drawing illustrating one manner in which my invention may be constructed the numeral 1 designates a stationary jaw to which is connected a shank 2 that has its free end formed into a handle 3. Teeth 4 are arranged along one edge of 40 the shank. Slidably supported by the shank is the movable jaw 5 which consists of a body portion 6 embracing the shank and the plate 7 bolted to the body portion and engaging behind the shoulder 8 of the body to 45 reinforce the rivets or bolts against a shearing stress. A handle member 9 has a loose connection 10 with a pin 11 so that the teeth 12 thereof may be accurately associated with the teeth 4 or readily removed from the teeth 50 4 so as to allow quick adjustment.

Besides the foregoing advantage the loose connection enables the upper end of the member 9 to abut the wall 13 so as to give

a more substantial bearing and prevent distortion of the pin 11. I have found out from 55 practice it is advantageous to have the gripping portion of one of the edges movable so as to accomplish a more accurate connection with the object acted upon. The gripping member 14 is provided with a pair of pintles 60 15 so that the member may have locking movement for effectively holding the member in place and at the same time allow it to be readily removed I provide a hole 16 in the body 5 and a hole 17 in the plate. From 65 this construction it will be seen that the gripping member is removably supported in a very substantial manner and allowed to have a rocking movement so as to assume the most advantageous position when gripping the object. 70

It is, of course, to be understood that the invention may be constructed in various other manners and the parts associated in different relations and, therefore, I do not 75 desire to be limited in any manner except as set forth in the claims hereunto appended.

Having thus described my invention what I claim is:

1. A wrench comprising a stationary jaw, 80 a shank connected thereto and having its free end formed into a handle and further having teeth formed along one edge thereof, a movable jaw mounted on the shank, a handle member having a displaceable connection with the movable jaw and provided with teeth for engagement with the teeth of the shank, and a gripping member movably connected to the movable jaw, said movable jaw consisting of a body portion embracing 85 the shank and a plate bolted to the body adapted to detachably hold the gripping member in place. 90

2. A wrench comprising a stationary jaw having a shank extension, a movable jaw 95 slidably on the shank, and a handle pivoted to the movable jaw constructed to have detachable engagement with said shank, and a gripping member, said gripping member having pintles projecting therefrom, and 100 said movable jaw consisting of a body having a hole receiving one of the pintles and a plate bolted to the body having a hole receiving the other pintle.

In testimony whereof I affix my signature. 105

PAUL JOHN TUMULLA.
